(57) **CLAIM**

The ornamental design for a wearable LED hair regrowth device, as shown and described.

DESCRIPTION

FIG. 1 illustrates a front perspective view of a wearable LED hair regrowth device;

FIG. 2 illustrates a bottom perspective view thereof;

FIG. 3 illustrates a front view thereof;

FIG. 4 illustrates a back view thereof;

FIG. 5 illustrates a left side view thereof;

FIG. 6 illustrates a right side view thereof;

FIG. 7 illustrates a top view thereof; and,

FIG. 8 illustrates a bottom view thereof.

The broken lines depict portions of the wearable LED hair regrowth device that form no part of the claimed design.
